Patented Oct. 29, 1974

233,479

COMBINED RADIO RECEIVER AND TAPE CARTRIDGE PLAYER

Andrew Kainass, Syracuse, N.Y., assignor to
General Electric Company

Filed Apr. 9, 1973, Ser. No. 349,130

Term of patent 14 years

Int. Cl. D14—03

U.S. Cl. D56—4 B

FIG.1

FIG.2

FIG.II

FIG.3

FIG.4

FIG.5

FIG.6

FIG.10

FIG. 7

FIG. 8

FIG. 9

FIG. 1 is a front elevational view of a combined radio receiver and tape cartridge player showing my new design;

FIG. 2 is a top plan view;

FIG. 3 is a bottom plan view;

FIG. 4 is a right side elevational view;

FIG. 5 is a left side elevational view;

FIG. 6 is a front elevational view of another embodiment of a combined radio receiver and tape cartridge player showing my new design wherein the front panels have been modified;

FIG. 7 is a top plan view thereof;

FIG. 8 is a right side elevational view thereof;

FIG. 9 is a left side elevational view thereof;

FIG. 10 is a bottom plan view thereof; and

FIG. 11 is a rear elevational view of either embodiment.

I claim:

The ornamental design for a combined radio receiver and tape cartridge player, as shown and described.
